DESIGN FOR A TOY

Clifford W. Judd, Rochester, N. Y.

Application April 25, 1945, Serial No. 119,183

Term of patent 3½ years

(Cl. D34—15)

To all whom it may concern:

Be it known that I, Clifford W. Judd, a citizen of the United States of America, residing at Rochester, in the county of Monroe and State of New York, have invented a new, original, and ornamental Design for a Toy, of which the following is a specification, reference being had to the accompanying drawing, forming a part thereof.

In the drawing:

Fig. 1 is a side elevation of a toy, showing my new design, and

Fig. 2 is a plan view of the same.

I claim:

The ornamental design for a toy, as shown.

CLIFFORD W. JUDD.
